UNITED STATES PATENT OFFICE.

ALFRED C. NELSON, OF LAKEWOOD, OHIO, ASSIGNOR TO THE WILLIAM B. POLLOCK COMPANY, OF YOUNGSTOWN, OHIO, A CORPORATION OF OHIO.

LADLE CAR AND LADLE THEREFOR.

1,405,065.

Specification of Letters Patent. Patented Jan. 31, 1922.

Application filed July 19, 1920. Serial No. 397,285.

To all whom it may concern:

Be it known that I, ALFRED C. NELSON, a citizen of the United States, residing at Lakewood, in the county of Cuyahoga and State of Ohio, have invented certain new and useful Improvements in Ladle Cars and Ladles Therefor, of which the following is a specification.

Among the objects of my invention are 10 the provision of a ladle-car having straight side frames instead of the customary depressed or "drop" side frames; the provision of a ladle-car having straight side frames without reducing the capacity of the ladle 15 for a given height and width as compared to ladle-cars of previous constructions having "drop" side frames; the provision of a ladle-car that may be built almost entirely of structural steel without the employment of 20 castings; the provision of a suitable ladle for use with a car having straight frames; the provision of a ladle having its upper portion 25 a solid of revolution about a vertical axis and its bottom a solid of revolution about a horizontal axis; the provision of a maximum capacity ladle which may be carried in a 30 ladle-car having straight side frames and which may be readily tilted therein for pouring.

Heretofore ladle-cars with which I am familiar have been constructed with "drop" or 35 depressed side frames in order that ladles of large capacity which may be carried by the car may be tilted for pouring without interfering with the side frames. This type of 40 depressed frame car is difficult and expensive to manufacture and the frames are weakened, in the direction of the severe end thrusts to which such cars are subjected in 45 service, to such an extent that various expensive expedients have to be employed in the construction of the cars in order to give them the necessary strength for supporting and transporting their extremely heavy loads.

In order to provide a ladle-car of simple construction and maximum strength yet having substantially the same capacity for its height and width as those cars previously 50 constructed with depressed frames I have devised a ladle which, while having its upper portion of full normal width or diameter, too great at its lower end to permit of tilting between the frames of the car for 55 pouring, has its sides cut away at the lower

end of its upper portion so as to permit the ladle to be tilted for pouring.

While my invention may be embodied in various forms, I prefer to use a ladle having its bottom the form of a solid of revolution 60 about a horizontal axis and its upper portion a solid of revolution about a vertical axis. The upper portion is customarily and preferably frusto-conical, with its larger diameter at the top. Ordinarily flat or dished 65 circular bottoms have been used on these ladles. When such a ladle is tilted upon its supporting trunnions in the ladle-car, the wide bottom swings out over the side of the car so that the edge of the bottom would interfere with a straight side frame or platform body sill. This has made it necessary, 70 previous to my invention, to construct ladle-cars with depressed or "drop" side frames and has resulted in the weakening of the cars 75 as above described.

By providing a ladle having its sides cut away at the lower end adjacent the car frames the ladle may be tilted upon its trunnions without interfering with straight 80 frames which may consequently be made very much stronger for the same weight, or of the same strength for a much smaller weight of material in the frames as compared to the depressed or "drop" side frame 85 car.

In the preferred form of my invention the ladle has the lower end of its sides cut away only where they would, if not cut away, interfere with the frame of the car when the 90 ladle is being tilted for pouring. In other words the lower end of the ladle is cut away or rounded in the plane in which the ladle tilts. By making the upper portion of the ladle a solid of revolution about a vertical 95 axis, such as a frusto-cone inverted, and the bottom of the ladle a portion of a solid of revolution about a horizontal axis, such as a cylindrical shell, the ladle can be readily constructed of plate metal and the advantages of my invention secured.

The aforesaid objects and advantages together with others which will be apparent to those skilled in the art are attained by the use of my invention described in these specifications and shown in the accompanying drawings in which:—

Fig. 1 is a side view partly in section of a ladle-car built in accordance with my invention;

Fig. 2 is an end view partly in section of the car shown in Fig. 1;

Fig. 3 is a side view of the car shown in Figs. 1 and 2 with the ladle being tilted for a short pour;

Fig. 4 is a vertical transverse section of the ladle shown in Figs. 1, 2 and 3; and

Fig. 5 is a vertical longitudinal section of the ladle shown in Figs. 1, 2, 3 and 4.

- 10 Referring to the drawings, 1 and 2 represent the car trucks upon which is supported in any customary or suitable way the body or main platform-frame, 3, of the car. The side members, 4 and 5, of the main frame, 3, are preferably made straight thus providing a structure capable of withstanding maximum end-thrusts and transverse bending moments. The side frame members, 4 and 5, are preferably made of rolled structural shapes such as the I beams shown in the drawings. Immediately over the trucks the platform body, 3, of the car may be constructed in any suitable manner, preferably of rolled structural steel shapes, such as the channels, 6, running longitudinally of the car and I beams, 7 and channels 8, running transversely of the car and which are shown riveted and reinforced at the joints in a well understood manner to form a strong platform body for the severe duty which it has to perform. Running transversely of the car, supported upon the side frames, 4, 5, and longitudinal frame members, 6, are the beams, 9 and 10, which are preferably made of rolled structural steel such as the I beams shown in the drawings and which form the main supports for the ladle, 11. Upon the cross members, 9 and 10, are supported the ladle trunnion chairs or bearings, 12, 12, 13, 13. It will be seen that at the middle of the car there is an open well or ladle receiving opening formed between the side frame beams, 4, 5, and the cross frame beams, 9, 10.
- 45 The ladle, 11, which I prefer to use, has its upper portion of customary frusto-conical or tapered shape, circular in horizontal cross section with the largest diameter at the top. The bottom of the ladle however differs in an important particular from ladles heretofore used, in that the bottom, 14, is formed of a portion of a solid of revolution about a horizontal axis and is preferably of cylindrical shape. The ladle, 11, 50 is preferably made of plate metal, the sides being joined to the bottom member, along the lines of intersection of the conical with the cylindrical portions, in any suitable way such as by riveting the overlapped edges or by welding or in any other suitable manner.
- 55 15, 16 and 17 are metal bands which encircle and reinforce the sides of the ladle.

Secured upon opposite sides of the ladle are the supporting and lifting trunnion brackets, 18, 19, provided with the sup-

porting trunnions, 20, 20, 21, 21, and the lifting trunnions, 22, 22. To the bottom of the ladle are secured the pouring hooks 23, 24, to which may be secured a steel rope or cable, 25, for connecting to the crane hook 70 when the ladle is to be tilted. To carry the rope, 25, in a convenient place, ready to use when needed, cable carrying hooks or brackets, 25^a, may be secured to the ladle and the rope may be hung loosely over one of them 75 and one of the pouring hooks, as shown in Fig. 1, when the rope is not in use.

In Figs. 2 and 3 of the drawings there is shown a steel rope or cable loop, 25, engaged with one of the pouring hooks and with the 80 crane hook, 26, in the act of tilting the ladle for pouring.

In Fig. 2 the ladle is shown being poured by pivoting upon its trunnions, 21, in supports, 13, of the car, while in Fig. 3 the ladle is shown while being poured pivoted upon its short pour brackets, 27, upon the short pour stands, 29. It will be seen that in either operation, that of pouring about its trunnion supports or that of making a short pour, the bottom, 14, has ample clearance from the straight side frames, 4, 5. This results from the shape of the bottom which is preferably made as shown in the drawings 90 of a rolled cylindrical flanged plate, 14, 95 which can very readily be produced and which can be joined to the main body of the ladle in a simple but strong and substantial union by inexpensive means.

In the handling of molten metal the ladle 100 is preferably lined with refractory material such as is shown at 30 to which the shape of the ladle lends itself readily. When the body of the ladle is made in the form of a solid of revolution about a vertical axis, the 105 pressure of the liquid, molten metal in the ladle does not tend to distort the shape of the ladle and to thereby crack the refractory lining as it does in ladles of other shapes.

It will be seen that the shape which I 110 have given to the bottom of the ladle does not appreciably change the capacity of the ladle and that it is substantially of the same capacity as those ladles heretofore made with flat or dished bottoms but which require depressed or "drop" frame cars in order that the ladle may be tilted for pouring, moreover, the overall height and width of a ladle car constructed in accordance with 115 my invention are no greater than those of ladle cars of drop frame construction. Further, the center of gravity of my car is no higher and the total weight is very much less on account of the fact that my invention permits the car body and ladle supports to be constructed entirely out of rolled steel instead of steel castings as has been necessary in ladle cars heretofore made.

The platform body of the car may be 120 trussed and reinforced in any suitable man-

ner preferably by the use of rolled structural materials such as the angles and plates shown at 31, 32 etc.

Upon the platform body of the car there 5 may be supported the customary brake operating apparatus such as is shown at 33.

The operation of my ladle car is in every way similar to that of other ladle cars heretofore in use. In Fig. 2 of the drawings the 10 ladle, 11, is shown in upright position in full lines and in tilted position in dotted lines. When it is desired to tilt the ladle for pouring, a loop, preferably a steel rope, 25, is placed on one of the hooks, 23, 24, and 15 engaged by the crane hook, 26. The raising of the crane hook, 26, causes the ladle to tilt about its supporting trunnions such as 21, and the entire contents from the ladle may be poured in this manner. The car and ladle 20 shown in the drawings are designed for pouring on either side of the car and the ladle is provided with short pour brackets, 27, 28 which are used when it is desired to pour molten metal into mixers, pig casting 25 machines etc., provided with short pour stands, 29, coming close to the car as shown in Fig. 3. In this short pour operation the same flexible loop, 25, may be used for connecting one of the pouring hooks, 23, or 24, 30 with the crane hook, 26.

The advantages of my invention will be apparent to those skilled in the art and it will be evident that modifications of my invention may be made without departing 35 from its scope.

Having thus described my invention, I claim:

1. In a ladle car, the combination with a car body and means for supporting a ladle 40 thereon, of a tiltable ladle having its upper portion in the form of a solid of revolution about a vertical axis and its bottom portion horizontally cylindrical, said ladle having trunnions upon its upper portion resting upon 45 said supporting means, said ladle being tiltable about said trunnions.

2. A ladle-car having a body with straight side frames and provided with a ladle support, a ladle supported on said support and 50 extending downward between said side frames, the upper portion of said ladle being in the form of a solid of revolution about a vertical axis and the bottom of said ladle being horizontally cylindrical.

55 3. A ladle-car having a body with straight side frames, ladle trunnion supports on said body, a ladle having trunnions resting on said trunnion supports, the upper portion of said ladle being in the form of a solid of 60 revolution about a vertical axis extending downwards between said side frames below the tops thereof, the bottom of said ladle being horizontally cylindrical.

4. A ladle car having a body composed of 65 side and cross frames, ladle supports on said

body, a ladle on said supports, said ladle having a shell the upper portion of which is frusto-conical with its axis vertical and its larger diameter at the top, the bottom of said ladle being a horizontal cylindrical 70 shell intersecting said frusto-conical section and secured thereto at the intersection of said conical and cylindrical portions, said ladle extending downward between said side frames.

5. In a ladle-car having a body composed of side and cross frame members, ladle-trunnion supports on said body, a ladle having trunnions resting on said supports the axes of said trunnions being parallel with said side frames, the upper portion of said ladle being in the form of a solid of revolution about a vertical axis extending downwardly between said side frames, the diameter of said solid of revolution being too great at 85 its lower end to clear said side frames when the ladle is tilted for pouring, the lower end of said upper portion of said ladle being cut away at the sides adjacent said side frames to clear said side frames when said ladle is 90 tilted for pouring and the bottom of said ladle being formed to close said cut away sides of said ladle.

6. In a ladle-car having a body composed of side and cross frame members, ladle 95 trunnion supports on said body, a ladle having trunnions resting on said supports, the axes of said trunnions being parallel with said side frame members, said ladle extending downwards between said frame members 100 and having a substantially vertical upper portion and a bottom secured thereto, said upper portion being normally too wide at its lower end to permit of tilting between said frames for pouring but being cut away at 105 the sides adjacent said frame members to permit the ladle to be tilted between said frame members, said bottom being formed to close said cut away sides of said ladle.

7. A ladle car having a body composed of 110 side and cross frame members, ladle trunnion supports on said body, a ladle having trunnions resting on said supports, the axes of said trunnions being parallel with said side frame members, said ladle extending 115 downwards between said frame members, the body of said ladle being of such shape that if it were continued to the bottom of the ladle it would be too wide to permit of tilting for pouring, the bottom of said ladle 120 being a portion of a solid of revolution about a horizontal axis intersecting and joined to said ladle body at the line of intersection of said solid of revolution with said ladle body, said bottom being formed so as to clear said 125 frame members when said ladle is being tilted for pouring.

8. In a ladle car, the combination with the car body and means for supporting a ladle thereon, of a ladle having a bottom in the 130

1. form of a portion of a solid of revolution about a horizontal axis and a pouring hook secured to said bottom.
9. In a ladle car, the combination with the 5 car body and means for supporting a ladle thereon, of a ladle having a bottom in the form of a portion of a solid of revolution about a horizontal axis, a pouring hook secured to said bottom and a cable carrying 10 hook secured to said ladle.
10. In a ladle car, the combination with the car body and means for supporting a ladle thereon, of a ladle having a bottom thereof and a 15 cable carrying hook secured to said ladle.
11. In a ladle car, the combination with the car body having side sills and means for supporting a ladle upon said car body, of a ladle the upper portion of which has the 20 form of a solid of revolution about a vertical axis and the bottom portion of which has the form of a portion of a solid of revolution about a horizontal axis the generating line of said upper portion being tangent 25 to the central transverse vertical cross section of said bottom portion, the bottom of said ladle extending downward between said side sills.
12. In combination with a car having 30 straight side-beams, a ladle mounted thereon to tilt toward either side of said car, said ladle having its bottom portion depending between said side-beams of the car, the opposite sides of said bottom portion of the 35 ladle being shaped so as to avoid striking against said side-beams when the ladle is tilted to pouring position.
13. In combination with a car having straight side-beams, a ladle mounted thereon 40 to tilt on an axis extending longitudinally of the car, the lower end of the ladle depending between the side-beams to a point below the same, said lower end of the ladle being semi-cylindrical in shape on an axis 45 parallel with the tilting axis of the ladle so as to avoid striking against the side-beams when the ladle is tilted toward either side of the car.
14. In combination with a car embody- 50 ing a main frame having straight side-beams mounted upon a pair of trucks, a ladle tiltably mounted on said main frame and depending between said side-beams to a point below the frames of the trucks, said depending portion of the ladle being rounded off at opposite sides so as to avoid striking against the side-beams when the ladle is tilted toward either side.
15. In combination with a ladle car embodying a pair of straight side-beams, intermediate longitudinal beams terminating short of a point midway the length of the car to form a ladle-space or well midway the length of the car, and a series of transverse beams connecting said longitudinal 65 beams, one pair of these transverse beams being mounted on top of the longitudinal beams at the inner ends of said intermediate longitudinal beams, and a tiltable ladle mounted on this latter pair of transverse 70 beams and depending to a point below said longitudinal beams.
16. The combination of a ladle car having a body composed of side and cross frame members said side frame members being straight, ladle supports on said body, a ladle on said supports, the body of said ladle having the form of a solid of revolution about a vertical axis, extending downward between said side frame members and being 75 of such diameter that if it were continued to the bottom of the ladle it would strike the side frame member when being tilted for pouring, the sides of said body being cut away to clear said side frame members when the ladle is being tilted for pouring, said ladle having a bottom closing said cut away portions of said body.
17. In a ladle car, a body having straight, longitudinal side beams and transverse 80 beams supported thereon, said transverse beams being spaced apart to form with said side beams a ladle receiving opening, ladle supports on said transverse beams and a tiltable ladle carried on said supports, said 85 ladle extending downward in said opening between and below said side beams and having its bottom rounded in the plane in which the ladle tilts to clear said side beams when the ladle is tilted for pouring.
18. In a ladle car a body composed of a pair of straight, longitudinal, side beams one on either side of the car extending from truck to truck thereof and disposed outside of the car wheels, cross beams connecting 90 said side beams, and longitudinal beams intermediate said side beams terminating short of a point midway of the length of the car, ladle supports on said cross beams and a tiltable ladle upon said supports extending 95 downward between said side beams and having its bottom contracted at its edges to clear said side beams when said ladle is tilted.
- In testimony whereof I affix my signature. 115
ALFRED C. NELSON.
